MOTOR-OPERATED SHAVER

Fletcher L. Parham, Akron, Ohio

Application January 21, 1937, Serial No. 121,551

9 Claims. (Cl. 30—41)

This invention relates to apparatus for shaving and has particular relation to motor-operated shavers.

Heretofore, numerous motor-operated shavers have been placed on the market, but none have been entirely satisfactory for various reasons. One of the principal difficulties encountered in the use of the present types of motor-operated shavers is that, due to the tendency of the beard, for example, to incline angularly of the skin surface in the direction of the normal shaving stroke, the hairs either do not come into the path of the shearing cutters at all or the final result is an unevenly trimmed beard with ugly patches of stubble showing. Another difficulty is experienced with the present types of motor-operated shavers in that, due to the amount of pressure necessarily applied to the skin surface in attempting to get a close shave, and due also to the presence of sharp portions at the leading edges of the shearing cutters, the raised portions or mounds around the pores of the skin often become torn resulting in unsightly sore spots on the surface of the skin with the attending danger of infection. Because of these and other objectionable features it has heretofore been practically impossible to get a clean, close shave with any of the present types of motor-operated shavers.

One object of the invention is to provide means in a motor-operated shaver whereby the hairs normally tending to incline angularly with respect to the surface of the skin will be automatically drawn into the path of the shearing cutters to insure an even and close shave.

Another object of this invention is to provide a motor-operated shaver which will automatically stretch the skin surface, and, by flattening the mounds around the pores thereof, shear off the hair at a point which is normally beneath the skin level, thereby obviating the necessity of either applying hand pressure to the shaver or of endeavoring to stretch the skin with the free hand.

Another object of the invention is to provide a motor-operated shaver in which the necessity of having abrupt leading edges on the shearing cutters has been obviated, thereby eliminating the danger of infection by reason of the tendency of sharp leading edges to rupture the skin around the pores.

Another object of the invention is to provide a motor-operated shaver having means whereby the sheared hairs are carried away from the shearing cutters, thereby obviating the necessity

of frequent cleaning of the shearing cutters or the cutter head.

Another object of the invention is to provide means in a motor-operated shaver whereby the sheared hairs may be stored for future convenient disposal thereof, thus eliminating the litter usually attending the use of a motor-operated shaver.

Another object of the invention is to provide means in a motor-operated shaver for maintaining suction in the cutter-head thereof and utilizing said suction for cooling the shearing cutters.

Another object of the invention is to provide cooling means for the motor of a motor-operated shaver, said cooling means being utilized from a suction created in the cutter-head.

Another object of the invention is to provide a motor-operated shaver of the character described which can be economically manufactured and which is of such compact construction as to be easily handled by the user.

These and other objects are attained by means of the apparatus illustrated in the accompanying drawings and described below. It is to be understood that the invention is not limited to the specific form thereof shown and described.

Of the accompanying drawings:

Figure 1 is a plan view of a motor-operated shaver embodying the invention.

Figure 2 is an elevation of such a shaver.

Figure 3 is an enlarged cross-section taken on the line 3—3 of Figure 2.

Figure 4 is an enlarged cross-section taken on the line 4—4 of Figure 1.

Figure 5 is an enlarged end view taken substantially on the line 5—5 of Figure 3.

Figure 6 is a fragmentary cross-section, greatly enlarged, illustrating application of the shearing head to the skin, but before pulling action has been applied to the skin and hairs thereon.

Figure 7 is a view similar to Figure 6 after pulling action has been applied.

Referring to Figures 1 to 5, inclusive, of the drawings, 10 is a casing of suitable material, and of suitable shape and weight for easy grip in the hand. The casing may comprise of a lower chambered portion 11 and a cover 12 secured thereto by means of screws 13, 13. Within a large chamber 14 in the casing 10 there may be mounted a suitable motor or motivating unit 15, such as an electric motor, which may have a centrally driven shaft 16 mounted longitudinally of the casing 10. A socket 11* may be provided, at the small end of the casing 10, for retaining the plug of a connecting electric cord 18. 55

Removably mounted in a grooved portion 11, at the enlarged end of the casing 10, there may be a cutter-head 18, a set screw 19 being provided to hold the latter in a fixed position. The cutter-head may comprise an outer relatively fixed shearing-cutter member 20, and a cooperating inner reciprocating or oscillating shearing-cutter member 21. Other forms of movable cutters may be used within the spirit of the present invention.

The outer shearing-cutter member 20 is essentially hollow and comprises a comparatively thick base portion 22, upper and lower walls 23, 23 converging therefrom to join an outer shearing plate 24, the latter being quite thin, a wall 25 closing one end and a plate 26 to close the other end. The plate 26 may be removably secured to the outer shearing cutter 20 by means of a screw 27 secured in the base portion 22. The shearing plate 24, for certain purposes of the invention, subsequently to be described, may be concave on the outer face thereof. Shearing plate 24 may be provided with a series of openings, such as narrow slots 28, 28 extending in parallel relation vertically across the face of the plate and terminating at points a short distance back of the edges or corners 29, 29 formed by the juncture of the shearing plate 24 and the top and bottom walls 23, 23. This provides a series of narrow cutting blades 28^a, 28^a between said slots 28, 28. These edges or corners 29, 29, which constitute the leading edges during the shaving strokes, may be provided with a slight radius to prevent rupturing or tearing of any raised portions on the surface of the skin, as for example the mounds 35 around the pores.

Slidably mounted within the outer shearing cutter 20 is the inner shearing-cutter member 21. The latter comprises a relatively thick base portion 30, and top and bottom walls 31, 31 converging therefrom to join an inner shearing plate 32. The outer faces of the walls 31, 31 and the shearing plate 32 fit snugly against the corresponding inner faces of the outer shearing cutter 20. On the inner cutter 21 there may be a series of openings, such as narrow slots 33, 33 corresponding to the openings 28, 28 in the outer shearing cutter 20, thereby providing a series of cutting blades 33^a, 33^a corresponding to the cutting blades 28^a, 28^a on said shearing cutter 20. For the purpose of urging the inner shearing cutter 21 outwardly against the outer shearing cutter 20 there may be provided spring-pressed balls 34, 34 in the base 22 of the outer cutter 20, which ride freely on the inner surface of the base 30 of said cutter 21 while the latter is being reciprocated. An oblong opening 35 may be provided in the base 30 of the cutter 21, adapted to receive an eccentric pin 36 on the end of the motor shaft 16. Rotation of the shaft 16 will then cause the inner cutter 21 to be reciprocated sufficiently to provide a shearing action between the shearing plates 24 and 32.

To carry out the invention means are provided to produce a suction at the outer end of the cutter head. While suction means could be connected to the shaver in various ways, it is preferable to build such a means into the shaver itself. To this end there may be a chamber 37, provided in the shaver, which is air tight except for an opening 38 in the wall of the casing 10 adjacent the cutter head 18, and a passage 39 in the conduit 40 extending from said chamber 37 along the bottom of the casing to the small end thereof. Within the chamber 37 a suitable suction-fan 41 may be fixed on the shaft 16 for the purpose

of creating a suction within the cutter-head 18. An opening 42 in the base 22 of the outer cutter 20, and plurality of openings 43, 43 in the base 30 of the inner cutter 21 are provided to connect the cutter-head with the fan.

The rush of air created by the suction-fan 41 obviously will have the effect of keeping the cutter-head 18 cool as well as to keep the motor-unit 15 cool by said rush of air passing through the chamber 37 and conduit 40.

If it is so desired a suitable receptacle, such as the vacuum bag 44, may be removably secured to the end of the conduit 40 for the purpose of collecting and storing the sheared hairs until they can be conveniently disposed of. This bag may be of the porous type commonly used in vacuum cleaners and may be provided at its outer end with a suitable spring clip 45 so it can be partially supported in unfolded condition by the connecting cord 15a.

In actual use the shaver herein described and illustrated is held at right angles to the surface of the skin, with the outer shearing plate 24 pressing gently against the skin, as shown in Figures 6 and 7. With the motor 15 running to drive the shaft 16, thereby operating the fan 41 to create a suction through the slots in the cutter head 18, as well as to cause a rapid reciprocating shearing action of the inner shearing cutter, the shaver is stroked gently back and forth along the surface of the skin, preferably in a direction in line with the slots in the cutter-head 18.

Due to various causes, the hairs and mounds surrounding the pores of the skin become flattened. This is true particularly in the case of the hairs of the beard which generally assume an inclination to the surface of the skin, in the direction of the normal stroke of an ordinary blade razor for example. The suction created by the fan 41 drawing air through the slots in the cutter head 18 tends to draw the flattened hairs from their angular positions, through the slots in the head 18 to straight positions in the path of the shearing cutters. By using a concave cutter head, the skin is drawn into the cavity of the head (see Figures 6 and 7) stretching the skin between the edges of the cutter head. This stretching of the skin tends to flatten the mounds of the skin surface and widen the gap between the individual hairs thereby decreasing the depth of the pore cavities from which the hairs grow, thus making it possible for the shearing cutters 20 and 21 to shear the individual hairs at points which would normally lie beneath the outer surface of the skin, as is best illustrated in Figure 7. Figure 6 shows the cutters 20 and 21 being applied to the skin surface, but without suction. Figure 7 is a similar view, but with suction applied, illustrating the manner in which the skin is stretched and the hairs drawn into the path of the cutters. It is to be understood that many advantages of the invention are attained if flat-ended cutter heads or cutter heads of convex or other shapes are used but the concave formation is considered preferable because of the stretching effect thus secured.

The shaver may be so designed, with respect to the depth of cut-back of the slots at the corners 29, 29 in the cutter head 18, and with respect to the amount of suction produced by the fan 41, as to give the user thereof a smooth, even shave with no stubble showing above the normal surface of the skin. By the use of the present invention, due to the lack of sharp corners at the leading edges 29, 29 of the cutter head 18, and because it is not necessary to apply excessive pressure to the skin,

the danger of damaging the latter is eliminated. In this way nature has a chance to heal any previous damage to the skin and restore it to a normal healthy condition.

5. Modifications of the invention may be resorted to without departing from the spirit thereof or the scope of the appended claims.

What is claimed is:

1. A motor-operated shaver comprising a motor, a cutter-head including an inner motor-operated movable cutting element, said cutter-head having a fixed concave outer cutting element, and means for maintaining suction at said cutter-head, the concavity of said outer cutting element being so formed and arranged that said suction will draw the skin therein for the purpose described.

2. A motor-operated shaver comprising a motor, a cutter-head including an inner motor-operated movable cutting element, said cutter-head having a fixed concave outer cutting element, and means for maintaining suction at said cutter-head, the concavity of said outer cutting element being so formed and arranged that said suction will draw the skin therein for the purpose described, said means comprising a suction fan in said shaver operable by said motor.

3. A motor-operated shaver comprising a motor, a cutter-head including a relatively fixed outer cutting element and an inner motor-operated movable cutting element, said outer cutting element including a concave cutter-plate, and means for maintaining suction in said cutter-head, the concavity of said cutter-plate being so formed and arranged that said suction will draw the skin therein for the purpose described.

4. A motor-operated shaver comprising a motor, a cutter-head including a relatively fixed outer cutting element and an inner motor-operated movable cutting element enclosed within said outer cutting element, said outer cutting element including a concave cutter-plate, and means for maintaining suction in said cutter-head, the concavity of said cutter-plate being so formed and arranged that said suction will draw the skin therein for the purpose described.

5. A motor-operated shaver comprising a motor, a cutter-head including a relatively fixed outer cutting element and an inner motor-operated movable cutting element enclosed within said outer cutting element, said outer cutting element including a concave cutter-plate, said outer and inner cutting elements having openings or slots therein adapted to receive the hairs to be sheared, and means for maintaining suction in said cutter-head, the concavity of said cutter-plate being so formed and arranged that said suction will draw the skin therein for the purpose described.

6. A motor-operated shaver comprising a motor, a cutter-head including a motor-operated movable cutting element enclosed within a rela-

tively fixed outer cutting element, said outer cutting element including a concave cutter plate, slots in said outer cutting element and in said movable cutting element adapted to receive the hairs to be sheared, said slots being cut back a portion from the face of said cutter-head, and means for maintaining suction at said cutter-head through said slots and said cut-back portions thereof.

7. A motor-operated shaver comprising a motor, a cutter-head including a motor-operated movable cutting element enclosed within a relatively fixed outer cutting element, said outer cutting element including a concave cutter plate, slots in said outer cutting element and in said movable cutting element adapted to receive the hairs to be sheared, said slots being cut back a portion from the face of said cutter-head, said cutter-head having substantially rounded corners at the leading stroking edges thereof, and means for maintaining suction at said cutter-head through said slots and said cut-back portions thereof.

8. In a motor-operated shaver, a hollow casing having a motivating unit therein, a hollow cutter-head removably fixed on said casing, said cutter head comprising a fixed outer shearing cutter having a concave cutter-plate thereon and a movable inner shearing cutter, a series of slots in the shearing plate of said outer shearing cutter, and a corresponding series of slots in the adjacent shearing plate of said inner shearing cutter, said slots being adapted to receive the hairs to be sheared, means connected with said motivating unit for moving said inner shearing cutter to shear said hairs, and means operated by said motivating unit for creating a suction within said hollow cutter-head through said slots in the outer and inner shearing cutters, the concavity of said cutter-plate being so formed and arranged that said suction will draw the skin therein for the purpose described.

9. In a motor-operated shaver, a hollow casing having a motivating unit therein, a hollow cutter-head removably fixed on said casing, said cutter-head comprising a fixed outer shearing cutter having a concave cutter-plate thereon and a movable inner shearing cutter, said cutter-head having substantially rounded corners at the leading stroking edges thereof, a series of slots in the shearing plate of said outer shearing cutter, and a corresponding series of slots in the adjacent shearing plate of said inner shearing cutter, said slots being adapted to receive the hairs to be sheared, means connected with said motivating unit for moving said inner shearing cutter to shear said hairs, and means operated by said motivating unit for creating a suction within said hollow cutter-head through said slots in the outer and inner shearing cutters.

FLETCHER L. PARHAM.
